Inventor:
Homer G. Knoderer,

by *Alexander S. Zunt*
His Attorney

UNITED STATES PATENT OFFICE.

HOMER G. KNODERER, OF BRIDGEPORT, CONNECTICUT, ASSIGNOR TO GENERAL ELECTRIC COMPANY, A CORPORATION OF NEW YORK.

OUTLET BOX.

Application filed December 31, 1923. Serial No. 683,550.

To all whom it may concern:

Be it known that I, HOMER G. KNODERER, a citizen of the United States, residing at Bridgeport, in the county of Fairfield, State of Connecticut, have invented certain new and useful Improvements in Outlet Boxes, of which the following is a specification.

The present invention relates to electric house wiring and more especially to outlet boxes for the reception of switches and other current controlling devices.

It is customary, in order to conceal the electric device, the box, and the opening in the wall for their reception, to provide a flush or wall plate thereover. This plate is provided with suitable openings through which project buttons or handles of the wiring device and is accordingly secured directly to the electric device so that the openings in the former will be in register with the buttons, handles, etc. In installing boxes in the walls of houses, it is ordinarily necessary either to adjust the position of the box to bring its front edge into alignment with the face of the plaster or else to introduce blocking out devices between the front edge of the box and the attachment lugs of the electric device, so that upon securing the latter to the box, it will be in position to support the plate against the face of the plaster.

The blocking out of the electric device from the front edge of the box is objectionable in that an open gap is left about the electric device unprotected by the box. Moreover, the blocking-out process and the box-positioning process consume much time of skilled workmen to effect.

The object of my invention is the provision of an improved outlet box which may be installed without regard to its relation to the face of the plaster and the electric device and its wall plate attached thereto without blocking or adjusting, and upon merely pressing against the front of the plate the several parts will be properly positioned and retained against displacement in service.

One embodiment of the invention is shown in the accompanying drawing, in which Fig. 1 is a vertical section of a plastered wall, an outlet box, electric switch and face plate in their desired relation; Fig. 2 is a front elevation thereof with part of the face plate broken away; Fig. 3 is a

perspective view of the box and its wall brackets, and Fig. 4 is a similar view of a wall bracket drawn to an enlarged scale.

The outlet box 1, shown in the drawing, is made of struck up sheet metal with integral lugs 2 bent outwardly from the front edges of its end walls and provided with tapped holes 3. Symmetrically with the lugs 2 the end walls of the box are each provided with a pair of parallel guide slots 4 extending from the front to near the rear of the end wall and adapted to slidably receive a wall bracket 5.

The wall brackets 5 are preferably made of springy metal, such as steel wire, with a straight central portion 6 lying in one plane, and two U-shaped loops 7 lying in a parallel plane and respectively connected at one leg 8 to the ends 6' of the central portion 6, while the opposite legs 9 are bent down into loops 10 disposed in parallel planes spaced to correspond with the spacing of slots 4 and at right angles to the first mentioned planes and the free ends thereof are formed into attachment lugs 11. The length of the central portion 6 will correspond with the spacing between the parallel guide slots 4 so that the connections 6' between the legs 8 and the central portion 6 will register with said slots and move more or less freely therein with the central portion 6 engaging the inner surface, while the U-shaped loops 7 engage the outer surface of the end wall of the box and the loops 10 will be disposed in the guide slots 4 to hold said parts from relative transverse movement, while the outer ends 11 are adapted to be secured to the framework 12 by screws 13.

The spacing between the parallel planes, in which lie the central portion 6 and the U-shaped loops 7, corresponds to the thickness of the box wall. By bending the connections 6' between the legs 8 and the central portion through an acute angle, the latter is made to engage the inside of the box wall in advance of the engagement of the legs 8 with the outside thereof, as shown in Fig. 1, and when the screws 13 are turned home in the framework, the bracket 5 is tilted outwardly somewhat on the legs 8 as a fulcrum and thereby a frictional grip is exerted at the points 14, 15 of the inner sides of legs 8 and the central portion 6 upon the opposite surfaces of the end wall of the box. By reason of the engagement of the central

portion 6 being in advance of the engagement of the leg 8, any outward movement of the box will be strongly resisted, whereas any inward movement is only slightly resisted.

Upon attaching the electric device 16 by screws 17 through its lugs 18 to the box lugs 2, and the face plate 19 to the device by screws 20 and pressing against the face plate 10 the rigidly connected plate, device and box will be displaced backward until the plate brings up against the face of the wall 21 where they are held automatically against forward movement by the gripping action 15 of the wall bracket 5, as above stated.

It will thus be observed that I dispense entirely with special adjusting devices and the trouble incident to their use and obtain a better and firmer positioning and retention of the several parts than is possible with a box dependent upon the degree of care with which its adjusting and holding means are manipulated.

While I have shown and described the best embodiment of the invention known to me, I do not desire to be restricted thereto.

What I claim as new and desire to secure by Letters Patent of the United States, is:

1. An outlet box provided with wall

brackets movably mounted thereon and having provision for automatically gripping and preventing outward movement of said box.

2. An outlet box provided with wall brackets mounted to slide thereon toward and away from the front edge thereof, said brackets having provision for automatically gripping said box and preventing outward movement thereof.

3. An outlet box provided with parallel slots extending forward and backward in the wall thereof, and wall brackets having a central portion disposed within said box and fulcrum portions connected with said central portion through said slots and disposed against the outside of said box.

4. An outlet box provided with slots extending forward and backward in the wall thereof and means for attachment of an electric device and a face plate thereto, and wall brackets slidably mounted in said slots and having provision for automatically gripping and retaining said box against outward movement when displaced inwardly by pressure exerted on the face plate.

In witness whereof, I have hereunto set my hand this 28th day of December 1923.

HOMER G. KNODERER.
